CLAIM

The ornamental design for a sink, as shown and described.

DESCRIPTION

FIG. 1 is a top plan view of a sink showing our new design;

FIG. 2 is a rear elevational view thereof;

FIG. 3 is a front elevational view thereof;

FIG. 4 is a bottom plan view thereof; and,

FIG. 5 is a left side elevational view thereof, the right side being a mirror image of the left side.

FIG. 2

FIG. 1

FIG. 4

FIG. 3

FIG. 5
